UNITED STATES PATENT OFFICE.

FRANK SAMLAND AND GEORGE SKOW, OF OMAHA, NEBRASKA.

SPARK PLUG.

Application filed March 27, 1922. Serial No. 547,013.

To all whom it may concern:

Be it known that we, FRANK SAMLAND and GEORGE SKOW, citizens of the United States, both residing at Omaha, in the county of Douglas and State of Nebraska, have invented new and useful Improvements in Spark Plugs, of which the following is a specification.

This invention relates to igniters for internal combustion engines, particularly to spark plugs, and has for its object the provision of a novel spark plug which has its ground terminal of peculiar formation whereby the spark will occur within the interior of a firing block, the protecting of the spark in this way preventing the fouling of the point inasmuch as the points are protected from oil at all times.

An important object is the provision of a spark plug of this character which is provided at its ground terminal with a firing plug formed with a plurality of intersecting holes through which extends the terminal electrode which is across the lower end 25 of the body of the plug.

An additional object is the provision of a plug of this character which will be simple and inexpensive in manufacture, which has great strength and durability and will consequently withstand hard usage, which will be positive in action, durable in service and a general improvement in the art.

With the above and other objects and advantages in view, the invention consists in the details of construction to be hereinafter more fully described and claimed, and illustrated in the accompanying drawings, in which:

Figure 1 is a side elevation of a plug constructed in accordance with our invention.

Figure 2 is a longitudinal sectional view therethrough, and

Figure 3 is a horizontal sectional view taken through the firing block.

Referring more particularly to the drawings, the numeral 10 designates the body of the plug which has its upper portion formed angular as shown for engagement by a suitable wrench and which has its lower portion reduced and externally threaded as indicated at 11 whereby to be engaged within the spark plug or hole of an engine. The lower portion of this body member is formed with a bore 12 while the upper portion is chambered and internally threaded as indicated at 13, this chambered portion being of

greater diameter than the bore 12 whereby to provide a shoulder 15.

Located within the body is a porcelain core 16 which is formed with an enlarged portion 17 which engages upon the shoulder 15, a suitable packing gasket 18 being provided between these parts. This enlarged portion of the porcelain core defines a shoulder 19 upon which is seated a suitable packing gasket 20 which is engaged by the lower end of the packing nut 21 which is screwed into the chambered out portion 13 and which has an angular upper portion 22 whereby it may be easily engaged by a suitable wrench.

The core 16 is of course provided with the usual longitudinally extending hole 23 through which passes the central electrode 24 which is provided near its lower portion 75 with an enlarged head 25 which fits within a recess 26 formed in the lower end of the core, this recess defining an abutment shoulder for the head 25. Disposed against the upper end of the core and of course disposed 80 upon the central electrode 24 is a suitable washer 26 upon which is engaged a lock washer 27 upon the top of which is engaged a nut 28 which is threaded upon the central electrode and which operates to hold it in 85 position. Also threaded upon the upper extremity of the central electrode is a binding nut 29 which provides means for attachment of the spark plug wire not shown.

The central feature of the present invention is the provision of a novel firing block indicated broadly by the numeral 30 and including a block member of suitable size and shape which is located at the lower end of the body 10 and which is formed with intersecting holes 31 which are drilled or otherwise formed therethrough. The central electrode 24 extends down through the upper portion of this block and terminates within the intersection of the holes 31 as 100 clearly shown. Extending from diametrically opposite points of the reduced lower end 11 of the body are lugs 32 which are opposite the ends of two of the holes 31, and secured to these lugs 32 is a transverse member 33 which passes through one of the holes 31 and which is of course spaced from the lower end of the central electrode 24 whereby to provide the necessary spark gap.

In the operation of the plug it will be 110 seen that the spark occurs between the lower end of the central electrode 24 and the trans-

verse wire member 33 which passes through the firing block. In this way it will be seen that the actual contact points are protected so that oil cannot splash onto them and as a result of this feature of the construction it is readily apparent that the plug should operate and be effective for a long time without any possibility of fouling or becoming sooted and consequently short circuited.

10 Owing to the peculiar construction and arrangement of the parts, it is apparent that the plug will not only be advantageous in this particular but it will also be capable of withstanding severe usage especially in 15 view of the strength of the parts and the specific manner of connection thereof with each other.

While we have shown and described the preferred embodiment of the invention, it 20 is of course to be understood that we reserve the right to make such changes in the form, construction and arrangement of parts as will not depart from the spirit of the invention or the scope of the subjoined claims.

25 What is claimed is:

1. In a spark plug, a metallic body, a core of insulating material secured therein, a central electrode extending through the core, a firing block carried by the lower end 30 of the electrode and provided with a plurality of intersecting passages and a metallic member traversing the open end of the

metallic body and passing through one of said passages in spaced relation to the walls thereof.

2. In a spark plug, a metallic body, a core of insulating material extending through the body, a block of conducting material located substantially within the skirt of the body and adjustably carried by the central electrode and a transverse pin carried by the skirt and projecting through a passage in the firing block in spaced relation to the wall thereof.

3. In a spark plug including a metallic body, a porcelain core secured therein, and a central electrode passing through the core and provided with securing means, a ground electrode structure consisting of a pair of lugs formed on the open end of the body at diametrically opposite points, a firing block located at the open end of the body and provided with intersecting holes, said block being furthermore provided with an opening into which extends the lower end 55 of the central electrode, and a transverse wire member passing through said lugs and through one of the holes in the block in spaced relation to the free end of the central electrode whereby to define a spark gap.

60 In testimony whereof we affix our signatures.

FRANK SAMLAND.
GEORGE SKOW.
